UNITED STATES PATENT OFFICE.

MARGARET E. PALMER, OF LOS ANGELES, CALIFORNIA.

DESIGN FOR A NURSING BOTTLE

60,567.

Specification for Design.

Patented Mar. 7, 1922.

Application filed July 2, 1920. Serial No. 393,723. Term of patent 14 years.

To all whom it may concern:

Be it known that I, MARGARET E. PALMER, a citizen of the United States, residing at Los Angeles, in the county of Los Angeles, and State of California, have invented a new, original, and ornamental Design for Nursing Bottles, of which the following is a specification, reference being had to the accompanying drawing, forming a part thereof.

Figure 1 is a front elevation of a nursing bottle showing my design.

Fig. 2 is a rear elevation of my nursing bottle, and

Fig. 3 is a cross section on the line 3—3 of Fig. 2.

I claim:

The ornamental design for a nursing bottle as shown.

MARGARET PALMER.
